UNITED STATES PATENT OFFICE.

WILLIAM HENRY JESSUP, OF POUGHKEEPSIE, NEW YORK.

FOLDING MECHANISM FOR PRINTING-PRESSES.

SPECIFICATION forming part of Letters Patent No. 586,903, dated July 20, 1897.

Application filed February 27, 1896. Renewed March 27, 1897. Serial No. 629,576. (No model.)

To all whom it may concern:

Be it known that I, WILLIAM HENRY JESSUP, a citizen of the United States, and a resident of Poughkeepsie, in the county of Dutchess and State of New York, have invented 5 certain new and useful Improvements in Folding Mechanism for Printing-PresSES; and I do declare the following to be a full, clear, and exact description of the invention, such as will enable others skilled in the art to which it appertains to make and use the same, reference being had to the accompanying drawings, and to letters of reference marked thereon, which form a part of this specification.

15 Figure 1 of the drawings is a representation of a section on line $x x$, Fig. 2, with delivery-frame shown down in dotted lines. Fig. 2 is a plan view of press. Fig. 3 is a detail view to show adjustability of rollers F F'. 20 Fig. 4 is a section through delivery-frame, showing belts P and means of operation. Fig. 5 is a plan view of the receiving end portion of the bridge conveyer or delivery and the sheet-centering devices thereon. Fig. 6 is a 25 sectional view of one of end bearings of roller B. Fig. 7 is a detail view showing more clearly the arrangement of one of the adjusting-screws N.

30 This invention has relation to certain new and useful improvements in the sheet conveyer or delivery mechanism used in connection with printing-presSES and folders for taking the printed sheet from the press and delivering it to the folder.

35 The invention is more particularly designed for use in connection with what is known to the trade as the "Kendall folder," and has for its object the provision of means for preventing the sheet as it leaves the tapes of the bridge conveyer which connects the folder proper with the press from curling or turning upwardly, according to its tendency, especially when the machine is so situated that it is subject to a draft or current of air.

40 A further object of the invention is to provide an improved construction of the frame of the conveyer or delivery whereby when the folder is not in use it may be dropped down against the folder-frame without straining the tapes.

45 Other objects will hereinafter appear.

With these objects in view the invention consists in the novel construction and combination of parts, all as hereinafter described, and pointed out in the appended claims. 55

In the accompanying drawings I have shown only the upper portion of the folder-frame and mechanism which is necessary to the understanding of the invention.

60 In the drawings the letter A designates the folder-frame, and B B' the rolls, which carry the usual series of tapes C, which receive the sheet from the delivery or bridge conveyer. Said rolls are journaled one at the front and one at the rear portion of the said 65 frame in adjustable bearings in the usual manner, or it may be in the special bearings hereinafter described. Immediately above the front roll B, I journal a second and similar roll B³, from which I extend a series of 70 endless tapes B⁴ to the forward roll D, which carries the upper tapes E of the bridge conveyer or delivery. In order to hold said tapes B⁴ down in proper relation to the lower tapes C, I provide two idle-rolls F F', one at the 75 front and one at the back, which depress said tapes in the manner shown clearly in Fig. 1. Said rolls are carried by vertically-adjustable brackets f, secured to bars A' of the frame. By the adjustment of these brackets 80 the action of said rolls upon the tapes may be accurately regulated. I have found that as the sheet leaves the upper and lower tapes E E' of the conveyer or delivery and passes between the tapes C B⁴ it has a tendency 85 to curl backwardly against the roll D, notwithstanding the tapes B⁴, which are some distance apart, and to prevent this I extend from the rearmost idle-roll F to the roll D a series of short tapes H, which are disposed in- 90 termediately with relation to both the tapes E and B⁴. These short tapes effectually prevent the above-described tendency of the sheet, and they also enable me to employ a much less number of the tapes E and B⁴. 95

I designate the two rolls between which the sheet passes downward to the vertical tapes I in making the first fold, and J is the usual blade. The upper tapes B⁴ effectually prevent all tendency of the paper to turn or 100 curl upwardly in passing to these rolls I.

I will now proceed to describe the second

feature of the invention, which relates to the construction of the bridge conveyer or delivery frame.

K designates the frame upon the cross-bar 5 k, on which are carried the usual series of brackets K', in which are the pulleys K², around which and the roll B' the lower series of tapes E' pass, said frame being hinged or pivoted upon the end portions of the shaft of roll B'. The free or receiving end of this frame when in use is suitably supported upon the frame of the press. (Not shown.)

L designates two rearwardly-projecting arms which pivot on the shaft of roll D, one 15 at each side of the machine. In these arms L is journaled the roll M, around which and the said roll D the upper tapes E pass. Each of said arms has in its under side an adjustable screw N, which rests upon the upper 20 face of the bar k of the frame K, and thereby supports said frame L in proper relation to the frame K. By this arrangement it will be seen that both of the said frames may be dropped down against the folder-frame when 25 not in use without, as indicated in Fig. 1, the necessity for removing the roll M and without any danger of straining the tapes. The bearings for said roll M are made adjustable at m in order that the tension of the tapes 30 may be properly regulated.

In Figs. 4 and 5 I have shown an additional feature which it is sometimes desirable to employ in connection with the mechanism above described for the purpose of properly 35 guiding or centering the sheet. This feature consists in providing at each side of the series of tapes E an endless edgewise-disposed belt P, which is in position to guide the edge of the sheet as it passes between the tapes E' E'. 40 These belts are carried by pulleys P' on short vertical shafts P², which are journaled in arms R, which are adjustably secured in the frame L. On each of the shafts P², which are nearest the roll M, is a bevel gear-wheel 45 S, which meshes with and is driven by a corresponding wheel S' on the shaft of said roll. The gears S' are preferably sleeved on the shaft of the roll M and held thereto by set-screws s in order that they may be adjusted 50 to correspond to the adjustment of the arms R, which is made to adapt the belts to sheets of different widths.

Considerable trouble has been experienced in this class of machines with regard to 55 curing the proper tension of the tapes, which are liable to changes in length resulting from changes in the condition of the atmosphere. I have therefore devised means in the nature of an automatic compensator which is de- 60 signed to overcome this objection.

Referring more particularly to Fig. 6 of the drawings, the letter T designates a bracket-arm which is designed to be adjustably bolted to the framework, as indicated in Fig. 1. 65 This bracket has therein a guideway t, in which is movably seated a boxing T', in the outer end portion of which is a bearing (such

as indicated at t') for the tape-carrying roller. Within the guideway of the bracket is a spring or springs T². Preferably two of these 70 springs are employed, their inner ends being seated against the inner wall of the guideway and their outer ends against the inner end of the boxing. The boxing is preferably provided with guide-rods T³, around which the 75 springs are coiled. One of the rollers of the pair carrying each series of tapes (the non-driving roller) is journaled in these boxes.

The action of the springs upon the boxes T' keeps the tapes properly stretched when they 80 would otherwise be slack, while at the same time they will readily yield to shrinkage of the tapes.

Having thus described my invention, what I claim as new, and desire to secure by Letters 85 Patent, is—

1. In mechanism of the class described, the combination with the rolls B, B', and D and with the tapes C carried by said rolls B and B' of the roll B³ journaled above the roll B, 90 the series of endless tapes turning from said roll B³ to the roll D, the vertically-adjustable idle-rolls F, F', and the series of short tapes running from the rear idle-roll F' to the said roll D, substantially as specified. 95

2. In mechanism of the class described, the combination of the folder having the rolls B, B', the endless tapes C carried by said rolls, the roll D above roll B', the roll B³ above roll B, the series of tapes B⁴ connecting the rolls 100 B³ and D, the vertically-adjustable idlers F, F', which depress the tapes B⁴, and the series of short tapes running from the idler F to the said roll D, together with the delivery or conveyer frame having the series of pulleys K² 105 and the roll M above said pulleys, the lower tapes E' running from said pulleys to the roll B', and the upper tapes E running from the roll M to the roll D, substantially as specified.

3. In mechanism of the class described the 110 combination with the folder-frame having the rolls B' and D journaled one above the other at the rear upper portion thereof, of the frame K hinged or pivoted to the folder at points concentric with the axis of roll B', the series 115 of pulleys carried by said frame, the tapes E' running from said pulleys to the roll B', the arms L pivoted to the folder at points concentric with the axis of the roll D, means for adjustably supporting the frame L upon the 120 frame K, the roller M pivoted in the arm L, and a series of tapes E running from the roll M to the roll D, substantially as specified.

4. In mechanism of the class described, the combination with the rolls B, B' and D, with 125 the tapes C carried by said rolls B and B', of the roll B³ journaled above the roll B, the series of endless tapes running from said roll B³ to the roll D, the vertically-adjustable idle-rolls F F' and the series of short tapes running 130 from the rear idle-roll F' to the said roll D, together with means for automatically regulating the tension of the tapes, substantially as specified.

5. In mechanism of the class described, the combination of the folder having the rolls B B', the endless tapes C carried by the said rolls, the roll D above the roll B', the roll B³ above the roll B, the endless tapes B⁴ carried by the said roll B³ and D, the idlers F F' and the series of short tapes running from roll D to the idler F', together with the delivery or conveyer frame having the series of pulleys K² and the roll M above said pulleys, the lower tapes E' running from said pulleys to the roll B', the upper tapes E running from the roll M to the roll D, and edgewise-disposed edge-guiding belts P, substantially as specified.

6. In mechanism of the class described, the combination of the folder-frame, having the rolls B' and D journaled one above the other at the rear upper portion thereof, the frame

L connected to the folder-frame adjacent to the roll D, the frame K connected to the said folder-frame adjacent to the roll B', a tape-carrying roller or pulley carried by the rear portion of each of the said frames K and L, the two series of tapes E E' carried by the said rolls B' and D', and the respective rolls or pulleys of the said frames, the edgewise-disposed edge-guiding belts P, one at each side of the series of tapes E E', the laterally-adjustable carrying-pulleys for said belts, and adjustable gear for driving the said pulleys, substantially as specified.

In testimony whereof I affix my signature in presence of two witnesses.

WILLIAM HENRY JESSUP.
